HARRY RIGGS, OF MIDDLETOWN, DELAWARE, ASSIGNOR OF ONE-THIRD TO EUGENE H. SHALLCROSS, OF McDONOUGH, DELAWARE.

CAR-COUPING.

1,120,242.

Specification of Letters Patent.

Patented Dec. 8, 1914.

Application filed April 19, 1913. Serial No. 762,426.

To all whom it may concern:

Be it known that I, HARRY RIGGS, a citizen of the United States, residing at Middletown, in the county of New Castle and State 5 of Delaware, have invented certain new and useful Improvements in Car-Couplings, of which the following is a specification.

The invention relates to improvements in car couplings.

10 The object of the present invention is to improve the construction of car couplings, and to provide a simple and inexpensive car coupling of strong and durable construction, having a pivoted knuckle and adapted to 15 couple automatically with all car couplings of the same general type, and capable of being readily uncoupled without going between the cars.

20 A further object of the invention is to provide a car coupling of this character, equipped with means for holding the knuckle locking mechanism out of engagement with the same to enable the knuckle to open freely and to obviate the necessity 25 of holding such locking mechanism out of engagement by hand until the cars are separated.

Another object of the invention is to provide an automatic car coupling, equipped 30 with a knuckle opening device adapted to be operated by the means for releasing the knuckle and arranged to be automatically reset or returned to its initial position by the knuckle in the closing movement thereof.

35 The invention also has for its object to provide a car coupling, adapted to be uncoupled in any position, and capable of coupling only when the parts are in proper operative position.

40 With these and other objects in view, the invention consists in the construction and novel combination of parts hereinafter fully described, illustrated in the accompanying drawings, and pointed out in the claim 45 hereto appended; it being understood that various changes in the form, proportion, size and minor details of construction, within the scope of the claim, may be resorted to without departing from the spirit or sacrificing any of the advantages of the 50 invention.

In the drawings:—Figure 1 is a vertical longitudinal sectional view of a car coupling, constructed in accordance with this 55 invention, the parts being locked. Fig. 2

is a similar view, illustrating the arrangement of the parts when the upper end of the knuckle releasing lever is at the limit of its rearward movement. Fig. 3 is a transverse sectional view, the vertically movable locking block being supported in an elevated position by the knuckle releasing lever. Fig. 4 is a horizontal sectional view, the parts being arranged as shown in Fig. 1. Fig. 5 is a detail perspective view of the pivoted knuckle. Fig. 6 is a detail perspective view of the knuckle opening lever. Fig. 7 is a similar view of the vertically movable locking block. Fig. 8 is a detail perspective view of the knuckle releasing lever.

Like numerals of reference designate corresponding parts in all the figures of the drawings.

In the accompanying drawings in which 75 is illustrated the preferred embodiment of the invention, 1 designates a drawhead of the conventional form provided at one side with a guiding arm 2 and having at the opposite side outwardly projecting upper 80 and lower perforated ears 3, between which is pivoted a knuckle 4 by a vertical knuckle pin 5. The knuckle consists of an outer engaging portion or jaw and an inwardly extending arm 6 operating within a horizontal chamber 7 of the drawhead and provided at its inner end with a curved lateral extension 8, projecting from the outer side of the arm and adapted when the knuckle 85 is closed to extend into an approximately rectangular recess or pocket 9 in the adjacent side wall of the drawhead. The arm of the knuckle is provided at the opposite side of its inner end with a flat face 10, adapted to fit against and be engaged by a 90 vertically slidable locking block or piece 11, having flat front and rear side faces and operating in a vertical guide 12 closed at the top and consisting of a hollow shell formed integral with the top of the drawhead. The 95 vertical guide, which forms a recess or pocket for the vertically movable locking block, has vertical front, rear and side walls, and it is of sufficient size to enable the locking block to move freely within it.

When the locking block is at the limit of its downward movement, as illustrated in Fig. 1 of the drawings, it extends partially into the vertical guide 12, and when the knuckle is released it is moved upwardly to a point 110

near the top of the guide by a knuckle releasing lever 13. The top of the guide 12 is inclined, and the upper face of the locking block is also inclined to conform to the configuration of the guide. By employing a closed guide of this construction, the drawhead is entirely closed at the top and snow, water, dust and other accumulation are excluded from the interior of the drawhead.

10 The lever 13, which swings longitudinally of the drawhead, extends through a vertical longitudinal slot or opening 14 in the bottom of the drawhead, and it is pivoted by a transverse pin 15 to a pair of ears 16, depending from the bottom of the drawhead and located at opposite sides of the opening 14. The lever 13 is substantially triangular being provided with tapered upper and lower portions and having a rearward taper, 20 the pivot 15 being located approximately midway between the top and bottom of the lever and in rear of the center thereof, whereby the front portion of the lever is heavier than the rear portion, and the lever rendered gravity acting to cause it to return automatically to its initial position. The upper arm or portion of the lever constitutes a cam for effecting an easy operation of the car coupling and the rear edge or face 30 17 of the said upper portion of the lever 13 is curved and arranged at an inclination extending forwardly and upwardly from the rear edges of the depending ears 16 when the lever is in its initial position, as illustrated in Fig. 1 of the drawings. The curved edge or face then occupies a position at the top of the lever and is located beneath the vertically movable locking block 11 and when the lever is oscillated, it is 40 adapted to engage the lower face of the said block 11, which is raised by the oscillation of the lever. The upper portion of the lever in swinging rearward first lifts the locking block and if the knuckle is not free to open 45 by reason of the cars being coupled, the point or upper end of the knuckle releasing lever will when it reaches the dotted line position illustrated in Fig. 2 of the drawings, engage behind the fixed catch 18 and 50 retain the locking block in an elevated position and the knuckle in a released condition, so that the said knuckle will be free to open without necessitating a brakeman or other person retaining the knuckle releasing lever 55 in such position by hand. The fixed catch, which is disposed transversely at the bottom of the locking block 11, has a beveled or inclined lower face and a vertical rear edge or face forming a shoulder to prevent the 60 lever from swinging forwardly out of engagement with the locking block.

Should the knuckle be opened while the upper end of the knuckle releasing lever is in engagement with the catch 18, the arm of 65 the knuckle, which is beveled at the upper

face of its rear end at 19, passes beneath the locking block and lifts the same sufficiently to disengage the catch 18 from the upper end of the knuckle releasing lever, and the latter will then swing forwardly and return by gravity to its initial position. The knuckle in its closing movement carries its arm 6 from beneath the locking block and permits the latter to drop into engagement with the said arm 6, the knuckle releasing 70 lever being in proper position to release the knuckle when desired. The knuckle releasing lever is provided at its lower end with an eye 20, and is designed to be connected with the operating mechanism usually employed for uncoupling cars, or with any other suitable operating mechanism to enable the operation of uncoupling to be performed at the sides of a car or platform of a coach without going between the cars. 85

A continued rearward movement of the upper portion of the knuckle releasing lever from the dotted line position illustrated in Fig. 2 of the drawings to the full line position shown in that figure carries the upper 90 end of the knuckle releasing lever into engagement with a knuckle opening lever 21 of angular or bell crank form, provided at the outer side of its angle with a rounded bearing lug 22, which fits in a vertical bearing recess 23, preferably formed by offsetting the adjacent side of the drawhead, as clearly illustrated in Fig. 3 of the drawings, but the wall may be constructed in any manner to provide a bearing recess of this character. 95 The knuckle opening lever consists of a forwardly or outwardly extending arm 24 and a rear transversely disposed arm 25, which is rounded at the bottom of its front face at 26 to coact with the curved face 17 of the knuckle releasing lever, whereby an easy movement of the parts is obtained. The forwardly or outwardly extending arm 24 tapers toward its front end, and its outer side edge is curved to conform to the configuration of the inner face of the adjacent side of the drawhead, and it is provided in its upper face with a transverse recess 27 through which the lateral extension 8 of the arm 6 of the knuckle extends. The front 100 end of the forwardly extending arm is rounded and when the lever 21 is oscillated in a horizontal plane through the action of the knuckle releasing lever 13, the forwardly extending arm 24 of the lever 22 engages the arm of the knuckle and swings the latter from the closed position, illustrated in full lines in Fig. 4 of the drawings, to the open position shown in dotted lines in the said figure. When the knuckle closes incident to 105 the automatic coupling of the cars, its arm 6 engages the arm 24 of the lever 21 and returns the latter to its initial position. The vertically movable locking block is provided at its rear portion with a lower transverse 110

115

120

125

130

recess 28 into which the transverse arm 25 of the knuckle opening lever extends when the knuckle is closed and the locking block is in engagement with the same. The 5 knuckle releasing lever after swinging the transverse arm 25 of the knuckle opening lever 21 rearwardly to the position shown in Fig. 2 of the drawings, automatically returns to its initial position as soon as the 10 operating mechanism is released by the operator.

What is claimed is:—

A car coupling including a draw head, a pivoted knuckle, a locking block slideable 15 vertically within the draw head and arranged to engage the knuckle, said draw head having means for guiding the locking

block, a horizontally swinging knuckle opening lever fulcrumed within the draw head and having an arm located in rear of the 20 locking block, a knuckle releasing lever pivotally mounted beneath the locking block and arranged to swing longitudinally of the draw head in a vertical plane and having a cam edge at its upper portion arranged to 25 successively engage the block and the knuckle opening lever to lift the former and oscillate the latter.

In testimony whereof I affix my signature in presence of two witnesses.

HARRY RIGGS.
